UNITED STATES PATENT OFFICE

2,562,063

FLOODLIGHT HAVING DIVERGENT ANGULAR HOOD FACES WITH HOOD LAMP APERTURES AND LAMP SOCKETS IN CO-AXIAL ALIGNMENT

Harry E. Rutledge, Pittsburgh, Pa.

Application December 3, 1946, Serial No. 713,619

1 Claim. (Cl. 240—3)

2

This invention relates generally to lighting units and more particularly to flood lighting units for illuminating areas around the base of the light and in projected areas extending therefrom.

The floodlight comprising this invention is particularly advantageous for use in lighting service stations, parking lots, railroad yards, transfer docks and the like.

The principal object of this invention is the provision of a floodlight arranged when supported in the air to provide a continuous light pattern from the base of its support outwardly.

Another object is the provision of a floodlight providing a continuous light pattern which extends substantially uniformly from the base outwardly.

Another object of this invention is the provision of a floodlight providing a clover leaf light pattern.

Another object of this invention is the provision of a floodlight composed of a plurality of sealed beam lights which combine to form a predetermined light pattern.

Another object is the provision of a floodlight composed of a series of sealed beam lights which do not depend on separate reflectors that constantly require cleaning to maintain lighting efficiency.

Another object is the provision of a floodlight that has a continuous maximum lighting efficiency.

Another object is the provision of a floodlight having a plurality of controlled beams which combine to provide an improved light pattern of greater intensity than a floodlight of materially greater wattage.

Other objects and advantages appear in the following description and claim.

A practical embodiment illustrating the principles of this invention is shown in the accompanying drawings wherein:

Fig. 1 is a prospective view of the hood or casing of the floodlight comprising this invention.

Fig. 2 is an enlarged sectional view of the floodlight with a portion of the hood removed and the sealed beam floodlights in position.

Fig. 3 is a sectional view taken on the line 3—3 of Fig. 2.

Fig. 4 is a top plan view of the complete floodlight.

Fig. 5 is a front elevation of the complete floodlight.

Fig. 6 is a view of the underside of the complete floodlight.

Fig. 7 is a view illustrating the light pattern produced by the floodlight.

Referring to the drawings, the floodlight hood 10 comprises the base member 11 and the cover member 12 which when assembled together as a unit as shown in Fig. 1 form a polyhedral casing.

The hood has six faces which make it substantially a hexahedral figure but only two of the opposite faces are substantially parallel with each other, namely, the under face 13 and the top face 14. The general contour of the base member 11 is in the shape of that of a triangular prism, the ends 15 and 16 of which are substantially parallel and the top 14 is disposed at an angle greater than 90° from the back 17. The front of the base member 11 opens downwardly and is bounded on the sides and along the top with the offset flange 18 arranged to receive the corresponding edges of the cover member 12, thus providing an overlapping joint that prevents the elements from entering into the hood when mounted in the proper position as indicated in Fig. 1.

The cover member 12 is also substantially of triangular prism shape having its sides 20 and 21 slightly converging toward the front of the hood. The front face of the cover member is divided into three section faces 23, 24 and 25, each of which are disposed in angular relation to each other. The end sections 23 and 25 slope away from the center section 24 as indicated in Fig. 6. To bring the three sections together under the flange 18 along the upper edge of the top 14 of the base member, the front face of the cover 12 is provided with an angularly disposed face 26 which mates with each of the sections 23, 24 and 25. The cover member 12 is secured to the base member 11 by means of the screws 27 passing through the flange 18 on the ends of the hood.

The three front faces 23, 24 and 25 of the hood cover member 12 are provided with annular seats formed by providing circular ridges 30, 31 and 32 around their respective openings 33, 34 and 35 which are cut, cast or otherwise formed in the three front faces.

The bottom of the cover 12 is provided with a centrally disposed opening 36 which may be fitted with a downwardly and forwardly projecting inner seat 37 that may be mounted as an independent part of the cover or it may be cast therein when the cover is formed. Since the seat 37 is disposed downwardly and forwardly and since the seats 33, 34 and 35 are each disposed at an angle to one another and to the seat 37, these seats provide means for properly locating the electric lamps that they are arranged to receive.

The base member 11 is provided with a strap light bracket member 38 shown in Figs. 2 and 3 arranged to be secured to the ends 15 and 16 by the bolts 39. This bracket is provided with three intermediate sections or seats indicated at 40, 41 and 42 which sections are disposed in planes substantially parallel with the plane of the respective sockets 33, 34 and 35 in the front face of the cover member 12. Electric light seats 43, 44 and 45 are secured to the bracket 38 on each of the sections 40, 41 and 42 and the centers of these

electric light sockets are disposed axially with the center of the seats 33, 34 and 35 of the front of the cover member 12.

Owing to the fact that the three faces 23, 24 and 25 on the front of the cover member 12 slope downwardly and rearwardly toward the bottom face 13 and are also disposed at an angle to each other, the electric lamp 46, arranged to be inserted in the electric socket 44 with its outer perimetral edge being received and held by the seat 34, places the beam of light from this lamp at a slightly higher elevation than the beams coming from the electric lamps 47 and 48, which may be seen in Fig. 2. Thus the alignment of the bracket together with the electric light sockets mounted thereon, cooperates with the sockets in the front face of the hood member 12 to properly align each beam of light for producing a predetermined light pattern.

The intermediate section 41 of the bracket 38 has secured to the rear side thereof a second bracket member 50, which has fastened thereto an electric socket 51 for the purpose of receiving the light bulb 52. This socket is secured to the bracket 50 by means of the spacer 53 and the bolt 54 which properly locate the light socket 51 relative to the seat 37 in the face 13 of the cover member 12. It is preferable not to secure the outer end of the bracket 50 to the base member 11 but to allow it to be free so that it may flex and insure proper alignment between the light seat 51 and the socket 37 when the light bulb 52 is screwed home and the glass bulb thereof engages the inner perimetral surface of the seat 37.

The seats 33, 34, 35 and 37 are arranged so that they may receive different sizes of adapters for the purpose of inserting sealed beam light bulbs of different shapes and wattages. In the structure shown the sealed beam lamps 46, 47, 48 and 52 are projector floods of 150 watts or greater and arranged to operate from a 115 volt circuit. As previously stated the shapes and sizes of these socket members may be changed to accommodate larger or smaller light bulbs having considerably more wattage.

The back 17 of the hood base member 11 is provided with a hollow swivel clamp member 55 having a central opening arranged to receive the bolt 56 for securing the hood to the socket member 57. The engaging faces of this clamp member are serrated as indicated at 58 to properly adjust the hood member at any desired angle. The socket member 57 has a hollow threaded bore 59 arranged to be screwed or otherwise attached to the top of the pipe section 60 for the purpose of mounting the floodlight and for carrying the wires to the electric light sockets therein.

The light shown is preferably positioned approximately 15 to 17 feet in the air to produce the light pattern illustrated in Fig. 7.

As shown in Fig. 7 the floodlight hood 10 is mounted on the top of the post 60 and produces a clover leaf pattern wherein the lamp 52 provides an intense circle of light 61 around the base and to the forward side of the floodlight. The lamp 52, being preferably of higher wattage than the other three lamps, provides a highly illuminated surface on the ground directly below

the floodlight. The beam of the central light 46 produces the extended central pattern 62 which intersects the perimeter of the beam pattern 61 and extends materially therebeyond. The beams 63 and 64 of the side lights 47 and 48 also intersect the pattern 61 and the adjacent pattern 62. However the beams of light produced by each of the lamps overlap one another to form a continuous light pattern, the general configuration of which is in the shape of a four-leaf clover.

In this manner a single floodlight fixture may be arranged to properly illuminate a considerably large area and owing to the fact that the lamps are of the sealed beam type they require very little service as they may be washed by means of a hose from the ground when they are not in service. Other types of lighting fixtures of this character employing separate reflecting surfaces must be cleaned frequently in order to obtain the proper light efficiency which they are designed to produce. Thus the floodlight comprising this invention provides a material improvement in the art.

25 I claim:

A floodlight fixture comprising a hood having three faces on the front thereof, the end faces of the three being symmetrically disposed at diverging angles relative to the center face, a face on the lower side of the portable hood directed downwardly and forwardly at an angle to each of the three faces, an annular seat defining an opening in each face to be engaged by a flood-lamp glass bulb larger in diameter than said 30 annular seat, an electric socket to receive the base of a floodlamp for each face, and means to mount each electric socket within the hood on the same axis as that of the corresponding annular seat of each face to hold the glass bulbs 35 against their seats making them coact to produce a predetermined floodlight pattern when the floodlamps are lighted.

HARRY E. RUTLEDGE.
